UNITED STATES PATENT OFFICE.

LUDWIG MARSHALL, OF BROOKLYN, NEW YORK, ASSIGNOR OF ONE-FOURTH TO
OTTO ZANDER, OF NEW YORK, N. Y.

AEROPLANE.

Application filed November 24, 1925. Serial No. 71,168.

The present invention is concerned with the provision of an aeroplane so constructed that it will automatically glide safely to the ground when for any reason the engine stalls or goes dead.

While the device is suitable for embodiment in various types of aeroplanes, I have shown a preferred form of the invention as applied to a monoplane.

10 A feature of the invention is the fact that it is not only well suited for incorporation in new planes, but may be readily applied as an attachment to old planes.

In its broader aspects, the invention includes the provision of a supplemental safety wing mounted above the body of the plane, and under normal conditions disposed in horizontal position. When the aeroplane starts to dive at a dangerous angle, either 20 because of engine trouble or unskillful handling, the safety wing acts automatically to throw the plane into gliding position.

It is an object of the invention to provide a relatively foolproof automatic mechanism for accomplishing the above noted results, and to provide mechanism of simple, practical construction which will not add materially to the weight of the aeroplane, and which is extremely unlikely to get out 25 of order.

With the above noted and other objects in view, the invention consists in certain novel features of construction and combinations and arrangements of parts, as will be 35 more fully hereinafter set forth and pointed out in the claims. The invention may be more fully understood from the following description in connection with the accompanying drawings, wherein—

40 Fig. 1 is a top plan view of an aeroplane embodying the invention.

Fig. 2 is a view in side elevation thereof.

Fig. 3 is a fragmentary vertical sectional view on the line 3—3 of Fig. 2.

45 Fig. 4 is a fragmentary longitudinal sectional view through the body of the plane, one of the housings for the supplemental wing supporting standards being broken away for clearness.

50 Fig. 5 is a fragmentary top plan view of the sliding section of the supplemental wing.

Fig. 6 is a diagrammatic fragmentary view partly in section and partly in elevation showing the sliding wing section projecting forwardly as the aeroplane reaches

a dangerous inclination, the dotted lines indicating another position of the supplemental safety wing.

Fig. 7 is a sectional detail of the mechanism for locking the safety wing against 60 movement.

Fig. 8 is a fragmentary sectional detail showing the guiding and stop means for the sliding section of the supplemental wing.

Fig. 9 is a longitudinal sectional view 65 through the forward edge of the supplemental wing and the sliding wing section.

Fig. 10 is a fragmentary top plan view of the cock-pit of the plane.

Fig. 11 is a sectional view on the line 70 11—11 of Fig. 10.

Fig. 12 is a transverse sectional view on the staggered line 12—12 of Fig. 11.

Fig. 13 is a side elevational detail showing the safety mechanism rendered inoperative by the locking lever. 75

For purposes of illustration I have shown a monoplane embodying the invention. It will of course be understood that various other types of heavier-than-air machines 80 might be constructed in accordance with the principles of the invention.

In the drawings, 10 represents the longitudinally tapered hollow body of the plane, provided at its forward end with the 85 cock-pit 11. The usual lifting wings 12 project laterally from the body adjacent the cock-pit, and the plane is equipped with the usual vertical steering runner 13 and horizontal tail pieces 14 including pivoted sections 14a. The forward end of the body carries suitable landing gear indicated generally at 15, and an engine 16 drives a propeller 17 of the puller type in any conventional or convenient manner. 90

The device as thus far described is entirely conventional, the present invention being more particularly concerned with the provision of a supplemental horizontal safety wing 18 supported above the body, 100 and acting automatically to direct or throw the aeroplane into a gliding angle when the plane dips or dives at a dangerous inclination. Before going into the details of the mechanism for operating the safety wing 18, it may be well to briefly outline the manner in which this wing acts. As best seen in Fig. 6, the wing 18 is pivoted at its intermediate portion on standards 19, and is normally disposed parallel to the lifting 105

110

wings 12. The wing 18 is formed with a gravitationally slideable extension 20 upon which is pivoted a lifting wing 21. When the aeroplane dips or dives at a dangerous angle, the sliding section 20 of the supplemental wing slides forwardly, and the lifting wing 21 is mechanically elevated to the dotted line position of Fig. 6. Air pressure under this wing tends to swing the entire safety wing unit approximately to the dotted line position of Fig. 6, or to such an angle that the wing 18 restores the body of the plane to a substantially horizontal gliding position, after which the sliding wing section 20 moves gravitationally to inoperative position, and the lifting wing 21 becomes inactive.

It is to be understood that the mechanism for normally latching the safety wing against movement, and for releasing said wing, the mechanism for effecting operation of the sliding wing section and the lifting wing 21, and in fact all of the mechanical instrumentalities by which I control the operation of the safety wing, are subject to a wide variety of modifications and variations. The mechanism illustrated is merely intended to show one efficient and practical means for mechanically controlling the proper functioning of the safety wing.

As best seen in Fig. 3, the wing 18 carries at opposite edges of its intermediate portion, depending brackets 25 fixed to the ends of rock shafts 26 journalled in the upper ends of the skeleton brackets 19 which rise from the body of the aeroplane at opposite sides thereof. Fixed on the outer ends of the rock shafts 26 are locking sector plates 27 having notches 28 in their edges. To lock the wing 18 against pivotal movement between the standards, I provide bolts 29 adapted to enter the recesses 28 in the sector plates 27. The bolts 29 are guided for movement in brackets 30 projecting outwardly from the standards 19, and contractile springs 31 act on the bolts and tend to move them to retracted position to effect release of the sector plates. The construction of the locking bolts is best seen in Fig. 7, wherefore it will be noted that the retractile spring is a coiled spring encircling the bolt 29, and disposed between the upper bracket 30 and a cross pin 32 on the bolt. The lower end of each bolt 29 is formed with an eye 33 adapted to be engaged by the hooked end 34 of a lever 35.

The levers 35 are fixed intermediate their ends on a transverse shaft 36, journalled in suitable bearings 37 in the standards 19. The lower ends of the levers 35 are connected by a cross bar 38. Coiled expansion springs 39 backed against lateral extensions 40 of the standards 19, engage the levers 35 near their lower ends and tend to swing them to the unlocking position shown in Fig. 6. Se-

cured to the cross bar 38 is one end of a cable or similar flexible device 41, this cable being led over a pulley 42 carried on a cross rod 43 supported between the standards 19 immediately below the cross bar 38. It will be seen that in order to properly lock the safety wing 18 against pivotal movement, it is necessary to exert tension on the cable 41, moving the levers 35 against the action of their springs 39 causing the hooked ends 34 of the levers to have a camming engagement with the eyes 33 of the bolts 29, and consequently projecting the bolts upwardly into locking relationship with the sector plates 27. The manner in which the cable 41 is operated to lock or unlock the safety wing will be more fully hereinafter described.

Referring now to Figs. 4 to 6, 8 and 9, it will be noted that the wing 18 which pivots approximately at its center on the rock shafts 26, is acted upon at opposite sides of its pivot by pairs of restoring springs 45 hooked into eyes 46 on the under surface of the wing, and anchored to the standards 19 as at 47. These springs tend to retain the wing 18 in substantial parallelism with the body of the aeroplane at all times, even when the sector plates have been released by the bolts 29.

The wing 18 is of light skeleton formation covered by cloth or other suitable material as is customary in aeroplane construction, and near its forward edge accommodates a sliding telescoping section 20. As best seen in Fig. 8, the section 20 carries laterally projecting pins or rollers 48 working in inwardly facing guideways or tracks 49 of the wing 18. The studs or rollers 48 engage the ends 50 of the guideways 49 to limit the inward or outward telescoping or sliding movement of the wing section 20. Secured upon the top of the sliding section 20 are brackets 51 mounting between them a transverse shaft 52 upon which a lifting wing 21 is pivoted at its rear edge. The lifting wing is rigidly connected to crank arms 54 to which are pivoted operating rods 55 carrying pistons 56 working in cylinders 57 secured to the sliding section 20. Relatively heavy inertia operated members 58, preferably in the nature of balls, travel in the cylinders 57. The inclination of the cylinders 57, relative to the wing section 20 is such that under all ordinary conditions the balls will rest in the bottom of the cylinders, but when the plane starts to descend at a dangerous angle, such as that shown in Figs. 6 and 9, the balls will gravitationally roll forward, striking the pistons 56 and acting through the operating rods 55 and crank arms 54 to swing the lifting wing 21 on its pivot, elevating the same to the position shown in Fig. 9. To normally prevent forward sliding movement of the wing section 20, and pivotal movement of the lifting wing

21, I provide a pair of pivoted levers 60, 61, the ends of which are attached to a cable 62 led over suitable pulleys 63 to crank arms 64 carried by the shaft 36. Levers 60, 61 normally project into the path of the stud 48 and the crank arm 54 respectively and lock the wing section 20 or the lifting wing 21 against movement. When the shaft 34 is rotated by the action of the levers 35, the cable 62 is pulled to release levers 60, 61 simultaneously with the release of the sector plates 28.

The means for controlling the cable 41 will now be described. Reference is to be had particularly to Figs. 4, and 10 to 13 inclusive, wherein it will be noted that 70 represents a rearward extension of the propeller shaft upon which I mount a centrifugal governor 71, this governor including the usual weighted arms 72 connected to a collar 73 fixed upon the shaft 70. The governor carries a yoke 74 connected by link 75 to a lever 76 pivoted in the upper end of a bracket 77 secured to the floor of the cockpit. The rear end of the propeller shaft extension 70 is journalled in the upper end of a standard 78 mounted upon the floor of the cockpit, and said standard carries at its upper end laterally projecting pins 79 working in slots 80 in the yoke 74, whereby to guide the sliding movement of the yoke and the governor. A coiled expansion spring 81 around the propeller shaft extension 70, and backed against the collar 73 normally urges the yoke rearwardly.

The cable 41, which as above noted, is trained over the pulley 42 and connected to lever 35, passes downwardly through an opening 83 in the body 10 under a guide pulley 84 and is connected directly to the rear end of the yoke 74. Thus when the shaft 70 is turning rapidly enough to hold the governor in a forward position, the cable 41 is maintained taut and the sector plates 28 and wing 18 locked against movement. Also at this time, the levers 60, 61 are held in locking position by their cable 62. When however, the speed of rotation of the shaft 70 decreases to such a point that the spring 81 is free to push the governor and yoke rearwardly, the tension on the cable is relieved and the springs 39 are free to act, rocking the levers 35, retracting the bolts 29, and moving the levers 60, 61 to unlocking position. Lever 76 is connected by cable 90 to a crank arm 91 (Fig. 2), which operates the rear pivoted sections 14^a of the horizontal tail pieces or rudders 14.

It will be noted that the pin 93 which pivotally connects the yoke 74 to the link 75, is laterally extended as at 94 into the path of a lever 95, which lever carries a spring pressed locking dog 96 coacting with sector plate 97. By swinging the lever 95 forwardly to the position shown in Fig. 13,

and releasing the locking dog, this lever will effectively prevent rearward movement of the yoke 75, by virtue of blocking rearward movement of the pin 94.

The mechanism which I have shown for steering the vertical rudder 13 forms no part of the present invention. This mechanism may conveniently include cables 100 connected to the rudder post 13^a and led through suitable guide pulleys 101 to a steering wheel 102 mounted in a vertical bearing frame 103, said bearing frame straddling the yoke 74.

While the operation of the device will be more or less apparent from the foregoing description, it may be briefly summarized as follows. When use of the safety wing is not desirable, as in stunt flying, the wing may be successfully locked in inoperative position by the simple expedient of moving the lever 95 forwardly. With the lever 95 moved to the rearward position of Fig. 4 however, the safety wing is free to operate. When the motor is started, rotation of the propeller shaft 70 acts through the medium of the governor 71 to tension the cable 41, acting through the mechanism above described to lock the sector plates 28 against movement, and to swing the levers 60, 61 to locking position. At the same time, through the medium of the lever 76, the cable 90 is tensioned, and the tail pieces 14^a held in horizontal position.

This position of all of the parts is maintained in the course of ordinary flying, the plane being perfectly free to assume a reasonable downward inclination without danger of tripping the safety mechanism. When however, the engine stalls or goes dead, or slows down to a dangerously low speed, the governor 71 moves rearwardly under the influence of its spring 81; consequently tension on the cable 41 is released, and the wing 18 is unlocked. Simultaneously the levers 60, 61 release the sliding wing section 20 and the pivoted lifting wing 21. The normal tendency of the plane with the engine stopped is to plunge downwardly, nose foremost. As the plane starts to dip, the wing section 20 slides gravitationally forwardly to its fully extended position, and when a dangerous angle has been reached, the balls 58 roll along their cylinders and mechanically lift the wing 21. At this time it will be remembered that the forward portion of the wing 18 is considerably wider than the rear portion, and that the only impetus necessary to cause pivotal movement of the wing is that afforded by the lifting wing 21. The air rushing in under the lifting wing, swings the entire safety wing 18 toward the dotted line position of Fig. 6, and the air pressure on the entire wing 18 quickly restores the plane to gliding position. When the wing has been tilted so that

its rear edge is below its forward edge, the wing section 20 gravitationally slides back into place, and the lifting wing 21 falls back into position. The springs 45 act at all times to restore the safety wing 18 to a position parallel with the body of the plane, and as the plane is righted or swung to horizontal position, these springs will restore the wing.

19 The above described action will be repeated until the plane safely glides to earth, or until the engine picks up. Of course, if the stalled engine can be started again, the relatching of the safety wing structure is 15 automatic as previously described.

It is to be noted that the operation of throwing the plane into gliding position is facilitated by the horizontal tail pieces 14^a, these pieces acting simultaneously with the safety wing to restore the plane. As the safety wing tilts upwardly, the tail pieces incline downwardly and the tail pieces and safety wing co-operatively act to bring the plane out of a sharp nose dive or dip, and back to substantially horizontal and gliding position.

Various changes and alterations might be made in the general form and arrangement of parts described, without departing from the invention. Hence I do not wish to limit myself to the details set forth, but shall consider myself at liberty to make such changes and alterations as fairly fall within the spirit and scope of the appended claims.

35 It is to be noted that the casings 19^a for the standards, offer a substantial surface area which acts to stabilize and prevent lateral sliding or rocking movement of the plane.

40 It is also to be understood that when the plane is in charge of an unskilled operator, and due to inefficient manipulation, starts to dive at a dangerous angle, the operator may release the safety wing even while the 45 engine is running at full speed, by simply pulling the lever 76 rearwardly.

I claim—

50 1. In an aeroplane including an engine, a supplemental safety wing pivotally mounted above the body of the aeroplane and normally held in substantial parallelism therewith, said wing being pivotally mounted intermediate its ends and acting automatically to restore the aeroplane to gliding position when the latter dives at a dangerous angle and the engine falls below a predetermined speed, and means under manual control of the operator for selectively releasing said wing or locking said wing against movement independently of the speed of the engine.

60 2. In an aeroplane, a supplemental safety wing pivotally mounted above the body of the aeroplane and normally held in substantial parallelism therewith, said wing

including a forwardly slidable extension adapted to be gravitationally projected forwardly when the aeroplane dives at a dangerous angle, and means under control of the aeroplane engine normally locking said extension against gravitational forward sliding movement.

3. In an aeroplane, a supplemental safety wing pivotally mounted above the body of the aeroplane and normally held in substantial parallelism therewith, said wing including a forwardly slidable extension adapted to be gravitationally projected forwardly when the aeroplane dives at a dangerous angle, and a pivoted lifting wing 70 75 mounted in said extension.

4. In an aeroplane, a supplemental safety wing pivotally mounted above the body of the aeroplane and normally held in substantial parallelism therewith, said wing including a forwardly slidable extension adapted to be gravitationally projected forwardly when the aeroplane dives at a dangerous angle, and a pivoted lifting wing 80 85 mounted in said extension, and mechanical means for initiating movement of the lifting wing.

5. In an aeroplane, a supplemental safety wing, standards pivotally supporting said wing between its ends above the body of the aeroplane and springs acting on opposite sides of the pivotal axis of the wing to normally retain said wing in substantial parallelism with the body, sector plates carried by the wing and bolts engaging the sector plates to prevent movement of the wing, and means under control of the engine for retracting the bolts and permitting the safety wing to function.

6. In an aeroplane, a supplemental safety wing pivoted intermediate its ends above the body of the plane, and normally maintained in substantial parallelism with said body, a gravitationally operable forwardly slidable extension associated with said wing, a lifting wing mounted on said extension, means under control of the engine of the aeroplane for locking the safety wing against movement.

7. In an aeroplane, a supplemental safety wing pivoted intermediate its ends above the body of the plane and normally maintained in substantially parallelism with said body, a gravitationally operable forwardly slidable extension associated with said wing, a lifting wing mounted on said extension, means under control of the engine of the aeroplane for locking the sliding section against movement.

8. In an aeroplane, a supplemental safety wing pivoted intermediate its ends above the body of the plane, and normally maintained in substantial parallelism with said body, a gravitationally operable forwardly slidable extension associated with said wing, a lifting 125 130

- wing mounted on said extension, means under control of the engine of the aeroplane for locking the lifting wing against movement.
- 5 9. In an aeroplane, a supplemental safety wing pivoted intermediate its ends above the body of the plane, and normally maintained in substantial parallelism with said body, a gravitationally operable forwardly slidable extension associated with said wing, a lifting wing mounted on said extension, means under control of the engine of the aeroplane for locking the safety wing against movement and locking the sliding section against 15 movement.
- 10 10. In an aeroplane, a supplemental safety wing pivoted intermediate its ends above the body of the plane and normally maintained in substantial parallelism with said body, a 20 gravitationally operable forwardly slidable extension associated with said wing, a lifting wing mounted on said extension, means under control of the engine of the aeroplane for locking the safety wing against movement, and locking the lifting wing against 25 movement.
- 11 11. In an aeroplane, a supplemental safety wing pivoted intermediate its ends above the body of the plane and normally maintained 30 in substantial parallelism with said body, a gravitationally operable forwardly slidable extension associated with said wing, a lifting wing mounted on said extension, means under control of the engine of the aeroplane for locking the sliding section against 35 movement.
12. In an aeroplane, a supplemental safety wing pivoted intermediate its ends above the body of the plane and normally maintained 40 in substantial parallelism with said body, a gravitationally operable forwardly slidable extension associated with said wing, a lifting wing mounted on said extension, means under control of the engine of the aeroplane 45 for locking the safety wing against movement, locking the sliding section against movement, and locking the lifting wing against 50 movement.
13. In an aeroplane, a supplemental safety wing pivotally mounted above and in substantial parallelism with the body of the aeroplane, a gravitationally operable forwardly slidable wing extension guided for movement in said wing, a lifting wing 55 pivotally mounted on the extension, crank arms connected to the lifting wing and gravity operated inertia members guided for rolling movement in the sliding section and adapted to act on said crank arms and initiate lifting 60 movement of the lifting wing.
14. In an aeroplane, a body, standards rising from the body, a supplemental safety wing pivotally mounted upon the standards, and housings for the standards offering relatively wide lateral surface areas to stabilize 65 the aeroplane and prevent lateral sliding thereof.

LUDWIG MARSCHALI.
